DEVICE FOR ENGAGING AND PULLING SLIDE FASTENERS

Leo Papagna, 2938 Dearborn St., Youngstown, Ohio

Filed Sept. 12, 1960, Ser. No. 62,115

Term of patent 14 years

(Cl. D17—3)

Figure 1 is a perspective view of a device for engaging and pulling slide fasteners, showing my new design;

Figure 2 is a side view thereof;

Figure 3 is a front view thereof.

The cord seen in Figures 2 and 3 is shown broken away for convenience of illustration.

I claim:

The ornamental design for a device for engaging and pulling slide fasteners, as shown and described.
